US0D1012884S

(12) **United States Design Patent** (10) **Patent No.:** **US D1,012,884 S**
(45) **Date of Patent:** ** Jan. 30, 2024

(54) **SPEAKER**

- (71) Applicant: **LG ELECTRONICS INC.**, Seoul (KR)
- (72) Inventors: **Seokkyu Kang**, Seoul (KR); **Youngsoo Han**, Seoul (KR); **Cheolwoong Shin**, Seoul (KR)
- (73) Assignee: **LG ELECTRONICS INC.**, Seoul (KR)

(**) Term: **15 Years**

(21) Appl. No.: **35/515,842**

(22) Filed: **Nov. 23, 2022**

(80) **Hague Agreement Data**

Int. Filing Date: **Nov. 23, 2022**
Int. Reg. No.: **DM/225423**
Int. Reg. Date: **Nov. 23, 2022**
Int. Reg. Pub. Date: **Dec. 23, 2022**

(30) **Foreign Application Priority Data**

- Jun. 24, 2022 (KR) 30-2022-0025349
